DEICING MEANS

Bernard Vonnegut, Boston, Mass., assignor to Research Corporation, New York, N. Y., a corporation of New York

Application July 3, 1943, Serial No. 493,386

10 Claims. (Cl. 244—134)

The present invention relates to the deicing of aircraft propellers and other exposed rotating parts of aircraft that are subject to icing during adverse flying weather.

The problem of preventing dangerous accumulation of ice on airplane propellers under icing conditions is particularly serious, as the ice which forms on the blades not only impairs the aerodynamic performance or "lift" by unfavorably modifying the blade shape, but also severely unbalances the propeller because of the building up and throwing off of heavy ice collections at random from one or another of the blades.

While several methods of ice removal from propellers have been used heretofore, none is particularly satisfactory. One method is to discharge an anti-freeze solution over the blade when icing is encountered. Another method involves coating the blades before take-off with a substance containing an anti-freeze. A third method involves heating the blades, either by electricity or by exhaust gases. Any system employing the latter method is naturally heavy and complicated, while the other methods provide only brief protection.

The present invention has as an object the provision of propeller deicing means for aircraft which is highly effective in preventing dangerous accumulations of ice on the blades, is completely automatic in operation, requires no heat or anti-freeze solutions, is light in weight and low in cost.

More specifically, the invention is concerned with the provision of means for automatically causing the ice to be thrown off by centrifugal force before the ice builds up to a thickness that seriously impairs the "lift" of the blade or causes appreciable propeller unbalance during shedding.

This result is achieved by the provision of means which substantially reduces the force required to remove the ice, so that the centrifugal force of even a thin coating of ice on the spinning blades is sufficient to cause the ice to shed. When ice forms on any surface, it has a very strong force of adhesion. For most surfaces, the adhesion is such that a shear stress of well over one hundred pounds per square inch is necessary to break the bond. If the ice forms on a rigid surface or on sheet material that is firmly fixed to a rigid surface, any force applied to the ice will 50 be transmitted uniformly to the rigid surface.

If, however, the ice forms on a sheet material that is more easily stretched than ice, then any force applied to the ice will appear as a concentrated stress at the edge of the ice. While the 55

total force applied may be relatively small, nevertheless because of the concentration of the shear stress at the edge of the ice, the stress in pounds per square inch at such zone may be well over that required to break the bond, and in such case the ice in that zone is freed from the material, with the concentrated shear stress then appearing at the edge of the ice that remains adhering.

The present invention makes use of this principle by applying to the propeller blade, or to portions of the blade surface most susceptible to icing, thin sheet material more stretchable than ice, so that the ice may form on this stretchable sheet material rather than on the surface of the blade itself. The sheet material is arranged to move and stretch, and under the influence of centrifugal force such movement and stretching occurs as the sheet material is loaded with increasing weight of ice. The result of the stretching movement is to apply concentrated shear stress to the ice at the edges of the formation, causing the ice to free itself progressively from the material until entirely removed. Because of this concentration of shear, the forces necessary to remove the ice are only a small fraction of the forces required when ice is formed on a rigid surface, and the result is that the ice is thrown off by centrifugal force before a dangerous thickness is built up.

Furthermore, the deicing means is constructed and arranged to cause the ice to be shed in relatively small fragments independently from a plurality of separate sections of the blade surface. This not only minimizes the possibility of damage to the aircraft from impact of the flying ice fragments, but also results, during flight under icing conditions, in the ice being shed from the propeller as a whole in a more or less continuous succession of small fragments, with consequently but little effect on propeller balance as the shedding proceeds.

The invention is likewise concerned with improvements in deicing means of the type which employs stretchable elastic sheet material around the leading edge portions of airfoils and other members which give rise, in their immediate vicinity, to non-uniform pressure distribution in the nature of aerodynamic "lift." More specifically, the invention provides a means for controlling or at least minimizing the tendency of such non-uniform pressure distribution or "lift" in the vicinity of the deicing means to disturb or displace the sheet material.

In the drawing illustrating the invention, Fig. 1 is a view of a propeller blade having stretchable

sheet material applied to the leading edge portion of the blade in accordance with the invention; Fig. 2 is a cross-section of the blade and stretchable sheet material, taken along the line 2—2 of Fig. 1; Fig. 3 is a similar cross-sectional view, showing a modified form of deicing means on a blade having a relatively sharp leading edge; Fig. 4 is a view of one form of stretchable sheet deicing means before attachment to a propeller blade; Fig. 5 is a sectional view on an enlarged scale of a portion of the material shown in Fig. 4; Fig. 6 is a view of a slightly modified form, taken in section similar to Fig. 5; Fig. 7 is an enlarged detail of one form of vent; Fig. 8 illustrates an alternative construction of deicing means prior to attachment to the blade; Fig. 9 is a sectional view thereof; and Fig. 10 is a diagram illustrating the manner in which the stretchable material causes a substantial concentration of shear stress at the edge of the ice under the influence of a force applied in the plane of the surface.

In the carrying out of the invention, the stretchable sheet material is applied to the propeller blade around the leading edge and over adjacent portions of the thrust and camber surfaces, indicated at 12 and 14 respectively, so as to cover the blade for roughly 20 per cent. of its chord, this being the zone most susceptible to serious icing. The deicing means may be secured to the blade by cementing with a cement appropriate to the sheet material used, which material may be thin sheet rubber or similar stretchable elastic material. In general, it is considered preferable to provide a backing piece or sheet which is secured to the propeller blade, the active ice-shedding material being carried by the backing piece.

Thus, in the embodiment illustrated in Figs. 4 and 5, the backing piece is indicated at 16 and the outer or deicing sheet material at 18. The backing layer is preferably though not necessarily of the same material as the deicing sheet, but somewhat thicker, to provide a resilient backing for the thin deicing material and thereby improve the abrasion resistance thereof. In certain applications, especially where the blade is thin and the leading edge relatively sharp, it may be advisable to employ as the backing layer a molded member, such as indicated at 17 in Fig. 3, shaped to provide for the deicing layer a radius of curvature around the leading edge not greatly different from that of the blade itself.

While the backing layer is preferably cemented to the blade over the entire surface of the strip, the deicing sheet 18 is secured to the backing layer only along its edges 20 and transversely at intervals along narrow lines indicated by dotted lines 22 to provide a plurality of individually stretchable units or areas. The spacing between transverse bonds preferably varies with the distance from the inner end of the blade, due to the variation in centrifugal force with radius for any given angular velocity. In the average blade, the centrifugal force varies by a factor of about five from shank to blade tip, hence the radial dimensions of the individual areas should theoretically vary by about the same factor. However, it may be desirable to vary the width of the material somewhat from shank to tip, in view of the wide variations in blade width and thickness, and hence the radial dimensions of the individual units may vary by some other smaller factor.

During the rotation of the propeller, the ma-

terial is subjected to centrifugal forces tending to stretch the material outwardly along the surface of the blade and under certain conditions to cause wrinkling of the material. In addition, except when the blade is set for zero angle of attack, the deicing material is subjected to pressure distributions which may tend to lift the material away from the blade. The tendency toward wrinkling may be avoided by applying the strips to the blade while the material is under tension longitudinally of the blade sufficient to prevent stretching to the point of wrinkling under normal operation with the material free of ice. Tensioning the material chordwise of the blade during application inhibits lifting of the material away from the blade. A convenient method of applying the material to the blade under tension involves soaking the deicing strip in benzene or similar hydro-carbon to cause swelling of the elastic material. The material is applied to the blade while in swollen condition, so that upon evaporation of the swelling agent, the material shrinks and is thereby tensioned.

To minimize frictional effects between the outer material and its supporting surface, such as the backing material, it is desirable, particularly where initial chordwise tensioning is to be employed, to lubricate the contacting surfaces of the material with graphite, talc, glycerine or other lubricant suitable for the elastic material.

An alternative method of minimizing the effects of reduced external pressures or "lift" on the deicing material is to create a partial vacuum beneath the material so that even though the pressure on the outer surface of the material drops substantially, nevertheless the pressure beneath the material is at least as low, so that the material is not distended or otherwise disturbed by entrapped air beneath the material.

An effective method of partially evacuating beneath any or all of the individual areas of stretchable material, and one which is applicable to deicing devices of the stretchable or elastic type, whether installed on propeller blades and operable by centrifugal force, or on wings or other airfoils and operated by forces other than centrifugal force, makes use of the non-uniform pressure distribution around an airfoil. By providing a series of vents in the deicing material beginning adjacent the leading edge and continuing at intervals back along the camber surface, as indicated at 24 in Fig. 2, it is possible to insure that over the range of angles of attack of the blade, one or another of the vents will be within or very close to the zone of lowest pressure around the airfoil. These vents are preferably in the nature of one-way valves, being merely small punctures or slits in the material and therefore normally closed by the elastic contraction of said material. The vents may conveniently be formed by making a narrow slash in the material oblique to the surface, as shown in enlarged detail in Fig. 7. When the vents are employed in propeller deicing material, they should be located along a line closely adjacent the radially outermost boundary of the area to be vented (see Fig. 2).

During operation, at the point of lowest pressure around an airfoil, the pressure drop may amount to several pounds per square inch below atmosphere. If this drop carries the pressure externally of the deicing material below that of the pressure within, then the vent which is in the zone of lowest outside pressure will open to permit outward flow and consequent equalization of pressure. The other vents, being subjected to pres-

sure differences in the opposite direction, remain closed.

As the result of the provision of a plurality of vents having one-way flow characteristics, it is evident that the pressure beneath the deicing material may be automatically maintained at a value low enough to prevent distension of the material due to aerodynamic lift, yet not evacuated to a point such that lateral or surface movements of the material under the influence of centrifugal force are unduly restricted by friction.

Instead of employing a construction in which the deicing surface consists of a plurality of areas each secured entirely around its boundaries, a construction such as indicated in Figs. 8 and 9 may be utilized, wherein the outer layer consists of units or areas which are secured along certain edges and left free along other edges, generally the radially outer edges. In certain cases, as in the illustrated embodiment, the outer sheet may be made up of individual sheets 28 of the stretchable material, arranged to overlap in the manner of scales, for example. These sheets are secured to the backing layer 30 along their side and inner edges, the outer edge of each sheet being free. As in the other embodiments, the deicing strip may be applied to the propeller either with or without initial chordwise tensioning. If it is desired to provide somewhat increased thickness of material over the leading edge of the propeller blade, so as to enhance the abrasion resistance of the deicing strip, the strips may be wider in their central portion, as by curving the outer edges 42, to increase the amount of overlap in this zone.

The manner in which the stretchable material operates to shed the ice under the influence of centrifugal force before any appreciable thickness has accumulated is illustrated in Fig. 10. Assume 36 to represent a portion of a sheet of stretchable material, secured at 38 to a rigid surface, while 40 indicates a formation of ice on the sheet material. Under the influence of centrifugal force acting in the direction of the arrow 43 and which increases as the ice builds up, the distribution of shear stress at different points along the interface is indicated in general by the curve 44. The ice formation 40, being relatively non-stretchable as compared with the material 36, is in effect supported only along a line of contact opposite the line of attachment of the stretchable material to the rigid surface. Thus the total mass of the ice formation 40 contributes to the shear stress at this point and consequently, before any appreciable thickness of ice can build up, the magnitude of the stress reaches a value, represented by the ordinate OA, sufficient to break the bond at the interface.

With the bond between ice and stretchable surface broken along a line nearest the line of attachment of the sheet material to the rigid supporting surface, the shear stress set up by the remaining mass of ice is concentrated along the innermost line, radially considered, at which any bond remains between ice and sheet material. The shedding process thus may be considered to take place progressively, starting from the inside edge of the area being considered. As a matter of fact, the shedding, once started, usually occurs so rapidly as to appear to take place simultaneously over the entire area. Under steady 70 icing conditions, any particular area will shed at fairly uniform frequency, when a thickness of the order of one sixteenth of an inch of ice has built up, but of course different areas will shed at different frequencies, so that generally the 75

total mass of ice on the blade at any one time does not fluctuate appreciably.

A comparison of the relative masses of ice which must be built up on rigid and on stretchable surfaces before shedding takes place under the influence of centrifugal force may be gathered from the upper part of Fig. 10. The area under the curve 44 represents the mass of ice that must accumulate before shedding takes place from a stretchable surface, while the area of rectangle OABC represents the mass of ice that must build up before shedding will occur from a rigid surface of corresponding area. That is, without concentration of shear stress, the ice thickness must at all points throughout the area provide a shear stress of magnitude OA to break the bond at the interface.

While certain specific embodiments of the invention have been shown and described, these are for the purpose of illustrating the invention and are to be considered in no way a limitation of the invention to the particular configurations and arrangements set forth.

I claim:

1. A propeller blade having deicing means comprising thin sheet material more stretchable than ice disposed around the leading edge of the blade and covering at least a portion of the thrust and camber faces of the blade, said material being secured marginally along lines radially of the blade and at intervals transversely to provide a plurality of independently stretchable ice intercepting surfaces adapted under the influence of centrifugal force on the ice to shed said ice through the action of progressive concentrated stress in shear.

2. A propeller blade having deicing means comprising thin sheet elastic material disposed around the leading edge of the blade and covering at least a portion of the thrust and camber faces of the blade substantially from shank to tip, a backing strip intermediate the elastic material and the blade and secured to the blade, said sheet material being secured to the backing material along lines which define a plurality of individual areas of sheet material, the material being free to stretch intermediate the secured portions, and means for partially evacuating the areas intermediate sheet and backing material comprising a plurality of vents disposed in the sheet material throughout a zone which includes the regions of minimum air pressure adjacent the blade over the range of the angles of attack within which the blade operates.

3. An airfoil having deicing means comprising elastic material more stretchable than ice disposed around the leading edge of the airfoil and covering at least a portion of the camber surface thereof, appreciable areas of the material being free of direct adhesion to adjacent surfaces beneath, means for venting beneath said unsecured areas to minimize the effect on said material of varying external pressure drops, said means comprising a plurality of normally closed apertures in the material adapted to open to permit pressure equalization when the pressure within the material exceeds the external pressure, said vents being disposed in the material throughout a zone which includes the regions of minimum air pressure adjacent the airfoil over the range of angles of attack within which the airfoil operates.

4. A propeller blade having deicing means comprising thin sheet elastic material closely conforming to and covering the leading edge portion of the blade, said material being secured at

spaced points to permit the material to stretch outwardly along the blade under the influence of centrifugal force.

5. A propeller blade having deicing means comprising a stretchable covering of thin sheet elastic material closely conforming to the blade contour, said material being disposed in independently stretchable marginally secured units along substantially the full blade length.

6. A propeller blade having deicing means comprising a stretchable covering of thin sheet elastic material closely conforming to the blade contour and covering at least the leading edge portion of the blade substantially the full length thereof, said material being disposed in independently stretchable marginally secured units of decreasing area from shank to tip of blade.

7. A propeller blade having deicing means comprising a stretchable covering of thin sheet elastic material closely conforming to and covering at least the leading edge portion of the blade substantially the full length thereof, said material being disposed in tensioned condition in independently stretchable marginally secured units.

8. A propeller blade having deicing means comprising a stretchable covering of thin sheet elastic

material closely conforming to and covering at least the leading edge portion of the blade substantially the full length thereof, said material being disposed in independently stretchable units lying in overlapping relation with the radially outer edge of each unit unsecured.

5 9. Deicing means for a propeller blade comprising a flexible backing strip adapted to cover the leading edge of a blade substantially the full length thereof, thin sheet elastic material secured to the backing strip along side edges and at spaced intervals transversely to provide a plurality of independently stretchable ice-intercepting surfaces.

10 15. Deicing means for a propeller blade comprising a flexible backing strip adapted to cover the leading edge portion of a blade substantially the full length thereof, thin sheet elastic material secured to the backing strip along side edges and at spaced intervals transversely to form a plurality of independently stretchable ice-intercepting surfaces, said sheet material having venting apertures extending therethrough to the backing material beneath.

20 25. BERNARD VONNEGUT.
